SWITCH POINT PROTECTOR

Filed Aug. 20, 1928

UNITED STATES PATENT OFFICE

ISAAC J. KILBURN, OF DENVER, COLORADO, ASSIGNOR TO THE AMERICAN SWITCH POINT PROTECTOR AND RAILROAD EQUIPMENT COMPANY, OF DENVER, COLORADO, A CORPORATION OF COLORADO

SWITCH POINT PROTECTOR

Application filed August 20, 1928. Serial No. 300,884.

This invention relates to railway switch-point protectors of the general type exemplified in my Patent No. 1,701,890, issued February 12, 1929, and its principal object 5 is to provide a device for the protection of a switch rail or switch point from wear and injury, that is readily applied to the rails or points of any standard switch without any alteration in the form and construction there- 10 of, which is adjustable to different positions on the rail and which is reversible whereby to double the period of its usefulness.

Other objects are to be found in the course of the following description with reference 15 to the accompanying drawings.

In the drawings in which like characters of reference designate corresponding parts throughout the views,

Figure 1 represents a plan view of a portion 20 of a railway switch showing the improved protectors in operative relation to the rails thereof,

Figure 2, an enlarged plan view of the protector and the switch parts with which it 25 is associated,

Figure 3, a face view of the construction illustrated in Figure 2, looking in the direction of the arrow A, and

Figure 4, a cross-section along the line 4—4, 30 Figure 3.

The tapering points or rails 5 of a railway switch are as usual connected for conjoint movement relative to the stock-rails 6 of the track, by means of rods 7 and 8.

One of the rods 7, commonly known as the number one rod, is fastened to the switch-rails by lugs or brackets 9 that are rigidly secured to the points by means of bolts 10, at 35 opposite sides of a web 9a and to which the rod is fastened by bolts 12. The bolts 10 are for the purpose of the present invention, replaced by bolts of somewhat greater length to secure the protectors in addition to the brackets.

Each of the protectors, as shown in the drawings, consists of a plate 13 placed between the switch-rail and the respective bracket and secured in place by the bolts 10, as stated hereinbefore.

The upper edge of the plate extends along-

side the tread of the rail to be engaged by the flanges of the wheels on passing railway cars and locomotives, and the plate is concaved lengthwise, as at 14, along its side engaging the rail to insure a firm contact under 55 all conditions.

The plate is beveled at its longitudinal edges to provide the tapering wear-faces 16 that in practice are engaged by the wheel-flanges, and for its connection to the rail, the 60 plate has two rows of holes 17 equidistantly spaced apart and extending at equal distances from its longitudinal edges.

The holes are for the purpose of receiving the bracket-bolts in different positions of the 65 protector or to admit in addition to said bolts other fastening devices that may be desired to further secure the plate.

It will be apparent that the protector may be reversed when one of its beveled contact-faces is worn away, to present its opposite corresponding face in operative relation to the tread of the switch-rail, and it will further be noted that owing to the provision of the multiplicity of symmetrically arranged bolt-holes, the position of the protector relative to the switch point may be varied according to different conditions.

It is preferred to make the protector of sufficient length to project beyond the free 80 end of the switch point, to further guard said end against wear.

The double-edge protector constructed as shown and described, is interchangeable between the two rails or points of a railway switch, i. e. it may be used at either side of the switch without any change in its form or construction.

What I claim and desire to secure by Letters Patent is:

1. A protector for switch-rails comprising a plate having parallel longitudinal wear-edges to extend along the tread of a switch-rail, and having bolt openings transverse to and at equal distances from said edges, for the application of bolts by which the plate is fastened to the rail.

2. A protector for switch-points comprising a plate concaved along one of its sides and adapted to be fastened to a switch-rail

with its concave side next to and spaced from the switch point, the plate having a wear-edge to extend along that upper portion of the switch point ordinarily engaged by the flange of a wheel moving along the point.

3. The combination of a switch point and a protector for same, comprising a plate apertured for the reception of bolts at different distances from its ends and having a wear-edge to extend along the tread of the switch point and bolts in the apertures fastening the protector to the switch point.

4. A protector for switch-rails comprising a plate having parallel longitudinal wear-edges and having two rows of bolt-holes at equal distances from said edges.

5. The combination with a railway switch including switch-rails, a connecting rod and lugs for fastening the rod to the rails, of a protector between a rail and the respective lug and having a wear-edge along that upper portion of the switch point ordinarily engaged by the flange of a wheel moving along the point, and bolts fastening the lug and the protector to the rail.

6. The combination with the point of a railway-switch, of a protector reversibly fastened thereto, and having one of two parallel longitudinal wear-edges extending along that upper portion of the switch point ordinarily engaged by the flange of a wheel moving along the point.

7. The combination with a rail of a railway-switch, of a protector plate bolted thereto and having one of two parallel wear-edges extending along the tread of the rail, the plate being reversible and longitudinally adjustable on the rail.

8. The combination with the point of a railway-switch, of a protector-plate fastened to the point and projecting beyond the free end thereof, the plate having a longitudinal wear edge extending along that upper portion of the switch point ordinarily engaged by the flange of a wheel moving along the point.

9. The combination of a switch point and a protector therefor extending along that upper portion of the switch point ordinarily engaged by the flange of a wheel moving along the switch point, the protector having a concave side whereby a portion of the protector is spaced from the side of the switch point.

55 10. The combination of a switch point and a concave protector therefor, the concave portion of the protector spacing a portion of the same from the switch point, and the protector having substantially parallel wear edges engaging the switch point at opposite sides of the concavity.

11. The combination with a switch point, of a reversible protector, adapted in either of two positions to engage a side of the point along that upper portion ordinarily engaged

by the flange of a wheel moving along the switch point, and bolts fastening the protector in either of its said positions.

In testimony whereof I have affixed my signature.

ISAAC J. KILBURN.
